UNITED STATES PATENT OFFICE.

CHARLES S. BARRELL, OF BOSTON, MASSACHUSETTS.

INTERNAL-COMBUSTION ENGINE.

Application filed August 21, 1919, Serial No. 318,861. Renewed October 23, 1925.

The invention to be hereinafter described relates to internal combustion engines, and more particularly to such engines of the two-cycle type.

5 It has been proposed to construct an engine of this type comprising a cylinder containing primary and secondary pistons. The primary piston is connected by a rod and crank with the shaft of the engine, and the secondary piston is operatively connected with a cam on said shaft. The construction is such that on the in-stroke of the secondary piston, the fuel charge is drawn into the space in the cylinder between the secondary piston and the head of the cylinder, and on the out-stroke thereof, the charge is transferred to the space between the pistons, where it is compressed and exploded to produce the power stroke of the primary piston. Then 10 the next in-stroke of the secondary piston serves to scavenge out the burnt gases from the cylinder through the exhaust port.

It has been proposed to provide valves in the secondary piston through which the fuel 25 charge drawn into the cylinder by said piston may be transferred to the space between the pistons. Since these valves are necessarily exposed to the products of combustion of the fuel charge, they are liable to become 30 carbonized and permit more or less leakage from the space between the pistons to the space between the secondary piston and the head of the cylinder, and thence through the inlet valve to the carburetor and from said 35 space through the opening in the cylinder head through which the stem for the secondary piston projects. Also, if the inlet valve for admitting the fuel charge becomes carbonized and leaks, there is further liability 40 of loss of power. Another object of the invention is to provide means for preventing leakage along the stem of the piston stem and past the inlet valve. Another object is to 45 provide means to prevent back fire from the explosion space, back through the secondary piston.

Another object of the invention is to provide yielding means in the connections between the secondary piston and its actuating 50 cam for reducing shock and wear on the cam from the sudden change in direction of the secondary piston at the ends of its strokes.

Another object of the invention is to provide means for cushioning the secondary pis-

ton as it approaches the limit of its outward 55 stroke.

Another object is to provide means to facilitate removal of carbon from the pistons.

Another object is to provide means to admit air into the explosion space between the 60 primary and secondary pistons to follow the burnt gases through the exhaust passage to prevent adulteration of fresh fuel charges by residual burnt gases.

With the aforesaid and other objects in 65 view, the character of the invention may be best understood by reference to the following description of one good form thereof, shown in the accompanying drawings, wherein:

Figure 1 is a view partly in vertical section and partly in end elevation of a plural cylinder two-cycle engine embodying the invention;

Fig. 2 is a side elevation of one of the cams for actuating the secondary piston;

Fig. 3 on an enlarged scale is a vertical section through one of the cylinders of the engine;

Fig. 4 on an enlarged scale is a vertical section through a portion of one of the cylinders;

Fig. 5 on an enlarged scale is a perspective view of a portion of the secondary piston, parts thereof being shown in section; and

Fig. 6 on an enlarged scale is a plan of the 85 secondary piston.

The engine may have any number of cylinders, but in the present instance, two cylinders or units 1 and 3 (Fig. 1) are shown conveniently disposed at a V-angle with respect 90 to one another and mounted on and connected by a casing 5 provided with brackets 7 for supporting the engine on the chassis of an automobile or other support. Since these cylinders or units are similar, a description 95 of one will suffice for both.

The cylinder 1, for example, may be provided with a head 9 (Figs. 3 and 4) detachably secured thereto by screw bolts 11, the walls of the cylinder and head being formed 100 hollow to provide the usual water jacket. The cylinder contains a primary piston 13 which may be connected by a rod 15 with a crank 17 on the shaft 19 journalled in suitable bearings 21 in the casing 5, referred to. 105

The cylinder also contains a secondary piston 23, in the present instance, formed of two parts 25 and 27 secured together by screws

29. The outer part of the piston may have a flange 31 adapted to project into an annular recess 33 formed in the head of the cylinder.

The fuel may be conducted from the carburetor 35 (Fig. 1) through an intake pipe 37 communicating with the port 39 in the cylinder, said port being provided with a spring-pressed puppet valve 41.

An important feature of the invention 10 consists in the construction and relation of the intake valve with respect to the secondary piston. This valve is located in the cylinder adjacent the head thereof in a position such that it is covered by the secondary piston 15 when the latter is in its outermost position. To prevent leakage of the gases of combustion from the space between the pistons outward along the inner wall of the cylinder to the inlet valve and to the carburetor, the secondary piston may be provided with suitable 20 leak-preventing means, such, for example, as packing rings 43 which will be at opposite sides of the inlet valve when the secondary piston is in its outermost position, as will be 25 noted in Fig. 3.

On the in-stroke of the secondary piston, a fuel charge will be drawn from the carburetor past the inlet valve into the space between the secondary piston and the head 30 of the cylinder. On the outward stroke of the secondary piston the fuel charge thus drawn in, is transferred to the space between the pistons. Suitable means may be provided for this purpose, in the present instance 35 of the invention, in the form of a plurality of spring-pressed puppet valves 45 mounted in and carried by the secondary piston, the construction being such that these valves will automatically remain on their seats on the in-stroke of the secondary piston, but will move from their seats on the out-stroke thereof to allow the fuel charge to pass into the space between the pistons.

Next will be described means for actuating 45 the secondary piston. In the present instance, this means comprises a stem 47 having one end thereof suitably connected to the secondary piston, this connection being preferably by a universal joint which may be in 50 the form of a ball 49 seated in a socket formed in the parts 25 and 27 of the secondary piston. The stem 47 projects outward through the head of the cylinder, a suitable stuffing box 51 being provided to prevent leakage from 55 the cylinder along the stem. Adjacent the outer end of the stem is a cross bar or member 53 connected to the outer ends of rods 55 which pass inward through suitable guides 57 and 59 projecting laterally from the head 60 and cylinder. The inner ends of the rods 55 may be provided with studs having rollers 61 working in camways 63 in a cam 65. In the present instance of the invention, each cam comprises two parts 67 and 69 detachably 65 secured together by bolts 71, and having

bosses 73 fast on the crank shaft 19, referred to.

The construction is such that opposed camways are provided in the parts of the cam adapted to receive the rollers on the opposite 70 ends of the studs carried by the rods 55, and the latter project through spaces 75 between the cam parts. As a consequence, a strong cam construction is provided for efficiently reciprocating the secondary piston. 75

The camway comprises a portion 77 (Fig. 2) of uniform radius extending nearly through an arc of 180°, a portion 79 of varying radius for rapidly producing the in-stroke of the secondary piston, and a portion 81 for rapidly producing the out-stroke of said piston. The portion 77 meets the portions 79 and 81 through portions 83 which may be gradually curved to reduce friction between the rollers and the camway as much 85 as possible. It will be noted that the camway is located eccentrically with respect to the crank shaft, and therefore, to avoid a greater mass of material at one side of the cam than the other, recesses 85 (Fig. 3) are 90 formed in the cam to produce a balanced construction which will have a uniform rotary motion.

While each of the cams, in the present instance, is formed of two parts containing opposed camways, it will be understood that in some cases a cam may be provided having a single camway. Also, in some cases a single cam may be provided for reciprocating the secondary piston if desired, instead of cams 100 at the opposite sides of the cylinder as shown herein. 95

The secondary piston is caused to engage the head of the cylinder during the explosion of the fuel charge, so that the reactive force 105 will be transmitted from the secondary piston to the head of the cylinder instead of to the cam or cams through the connections between the latter and the secondary piston. The secondary piston will engage the head 110 of the cylinder while the cam follower rollers 61 are working in the portion 77 of the camway having a uniform radius. Preferably, the camway and the connections therefrom to the secondary piston are such that the latter 115 will be moved by the cam outward until it engages the head of the cylinder, but to insure the seating of said piston against said head, the camway portion 77 may be of a width sufficient to leave a space 87 between the cam 120 followers 61 and the outer wall of the camway, so that the force of the explosion may press the piston against the head of the cylinder without interference from the camway, and therefore, without shock on the latter. 125

To further contribute to the efficient seating of the secondary piston against the head of the cylinder for the purposes described, the bar 53, referred to, may be yieldingly connected with the piston stem 47. To accom- 130

plish this, in the present instance, said bar has a hole receiving a portion of said stem, and coil springs 91 and 93 are confined between said bar and adjusting nuts 94 threaded on the 5 stem.

The construction is such that when the cam moves the secondary piston upward, the motion is imparted from the inner wall of the camway to the followers and thence through 10 the rods 55 to the bar 53. The latter in turn will compress the coil spring 91 and move the stem 47 and the secondary piston outward until said piston engages the head of the cylinder. The spring 91 thus energized, will 15 tend to press and maintain the piston against the head.

On the in-stroke of the secondary piston the motion will be transmitted from the bar 53 through the coil spring 93 to the stem 47 and 20 the secondary piston, and since on the out-stroke of the secondary piston the motion is imparted thereto through the coil spring 91, these springs will serve to tend to relieve the 25 cam from shock in changing the direction of movement of the secondary piston at the ends of its strokes.

In some instances it may be desirable to 30 provide means for cushioning the secondary piston as it approaches the head of the cylinder. For this purpose, in the present form of the invention, a coil spring 95 is provided mounted in an annular recess 97 in the cylinder head, the inner end of said spring being 35 suitably anchored in said recess, and the outer end of said spring being provided with a cap 99 for engagement with the secondary piston.

Next will be described means for preventing 40 loss of power from explosion in case the valves 45 in the secondary piston become carbonized and leak. This means, in the present instance, comprises a conical projection 101 on the secondary piston adapted to tightly 45 seat against a conical recess 103 in the cylinder head, the angle of said projection and recess being of sufficient degree to insure tight 50 engagement thereof without wedging of the projection in said recess so as to interfere with ready movement of the piston away from the head. The seal thus provided is located between the valves 45 and the piston stem 47. As a consequence, any leakage past said valves 55 will be unable to escape to and along said stem. To further contribute to the prevention of the leakage referred to, the piston and cylinder head may be provided with a conical projection 105 and a conical recess 107 similar to the projection and recess described, and located radially inward therefrom, although this second sealing means is not indispensable.

To further contribute to prevention of leakage, the secondary piston may be provided 60 with upstanding circular seats or rings 109 (Figs. 5 and 6) on its upper surface surrounding the valve ports and adapted to engage 65 similar seats or rings 111 (Fig. 4) on the in-

ner surface of the cylinder head. Preferably three valves are employed in the secondary piston, and since each valve is provided with rings as described, the secondary piston will seat against the cylinder head at three points. 70 This will tend to insure tight engagement of all three rings of the piston with all three rings of the cylinder head. To further prevent any possibility of such leakage, the piston may be provided with an upstanding ring 75 113 at the upper surface thereof encircling and outside of the three rings for the valve ports, and be adapted to engage a similar ring 115 on the inner face of the cylinder head encircling all three rings on the cylinder head. 80

It is important that on explosion of the charge between the pistons there should be no back fire such as might ignite the fresh fuel charge drawn in by the secondary piston between the latter and the cylinder head. Suitable means may be provided to prevent such occurrence, and in the present instance each of the valve ports may be covered by a gauze diaphragm 117 (Fig. 5) suitably secured to the piston. 90

To facilitate removal of carbon deposits on the inner faces of the pistons, two diametrically opposed exhaust ports 121 (Fig. 1) may be employed, the construction being such that the pipe connections 123 for the exhaust 95 ports may be removed, and then one can look through one of the exhaust ports while a tool is inserted through the opposite exhaust port and manipulated to scrape the carbon from the pistons. 100

After the explosion of a charge between the pistons, the secondary piston is moved quickly downward to scavenge or drive out the burnt gases. The rapid exit of said gases from the cylinder will produce a partial vacuum therein. To insure a fresh unadulterated new charge in the explosion space, an air admission port 125 may be provided in the cylinder at a point beneath the exhaust ports, so that as the primary piston moves downwardly, it will first uncover the exhaust ports to allow escape of the burnt gases, and then fresh air may be drawn in through the air port by the vacuum and follow the burnt gases out through the exhaust port, thereby 110 insuring the complete discharge of all burnt gases. When the primary piston moves upward, it will first close the air port and then close the exhaust ports. The secondary piston, however, is moved upwardly more rapidly than the primary piston, so that the fresh charge will be transferred from the space between the secondary piston and the cylinder head into the space between the two pistons, and this fresh charge will not be adulterated 120 by any residual burnt gases in the space between the pistons. 125

To provide lubricant for the stem of the secondary piston, a grease cup 127 may be mounted on the cylinder head and feed lubri- 130

cent to the portion of the stem which reciprocates through the head. This lubricant may gravitate downward along the stem toward the ball of the universal joint at the lower end of the stem. The piston may have a circular groove 129 adjacent the stem to catch lubricant and guide the same inward toward the ball on the end of the stem.

10 A spark plug 131 (Figs. 1 and 3) may be connected to the cylinder at a point to ignite the compressed fuel charge between the pistons.

As shown herein, two cylinders are provided, disposed at a V-angle, and one cam 13 may serve both cylinders, since a plurality of followers may work on the same cam and have connections leading therefrom to the secondary pistons of the cylinders. While two cylinders are shown herein, it will be 20 understood that the engine might have four or more cylinders, all served by the same cam if desired.

The construction of the camway of the cam for reciprocating the secondary piston is such that said piston is moved quickly 25 downward away from the head of the cylinder and quickly back toward said head. The radii of progressive points of the camway for moving said piston down and up 30 rapidly, vary considerably in length until the piston almost reaches the head of the cylinder, and is, for example, about one-half inch from said head. The radii of progressive points on the camway in moving the piston 35 through this final one-half inch distance, vary but slightly. As a consequence, the piston is slowly moved by the cam through this last one-half inch distance to the head of the cylinder, and pounding of the piston 40 against the head of the cylinder is prevented. The piston is thus seated against the head of the cylinder, and the reactive force of the explosion is borne by the head of the cylinder rather than the connections between the secondary piston and the actuating cam 45 therefore.

In operation, the secondary piston will be moved downward to draw a fuel charge 50 through the inlet port into the space between the secondary piston and the cylinder head, and in the course of this movement will scavenge out the burnt gases resulting from the previous explosion. Then the secondary piston will move upward and force the fuel 55 charge thus drawn in past the valves 45 into the space between the pistons. The primary piston will follow the secondary piston in its upward movement and compress the fuel charge between them, said charge being then 60 ignited, and causing the power stroke of the primary piston. During the explosion of the charge the secondary piston will remain seated against the head of the cylinder, so that the reactive force of the explosion will 65 be transmitted from the secondary piston to

the cylinder head, and not to the actuating cam therefor.

Certain features of the internal combustion engine disclosed herein are made the subject of a divisional application Serial 70 No. 65,327, filed October 28, 1925.

It will be understood that the invention is not limited to the specific embodiment shown, but that various deviations may be made therefrom without departing from the spirit 75 and scope of the appended claims.

What is claimed is:

1. A two-cycle internal combustion engine, comprising, in combination, a cylinder, primary and secondary pistons therein, a shaft, a crank and rod connecting said primary piston with said shaft, connections between said shaft and secondary piston for reciprocating the latter, valve means for transferring a fuel charge 85 from the outer to the inner side of said secondary piston, means independent of the valve means for preventing the gases of combustion from escaping through the valve means during an explosion. 90

2. A two-cycle internal combustion engine, comprising, in combination, a cylinder, primary and secondary pistons therein, a shaft, means connecting said primary piston with said shaft, an inlet valve in said cylinder adjacent the head thereof covered by said secondary piston when at the limit of its outward stroke, and piston rings on said secondary piston at opposite sides of said inlet valve when said secondary piston is at the 100 limit of its outward stroke.

3. A two-cycle internal combustion engine, comprising, in combination, a cylinder, primary and secondary pistons therein, a shaft, a crank and rod connecting said primary piston with said shaft, means for reciprocating said secondary piston including a cam formed to hold said secondary piston stationary during explosion of the fuel charge, and an inlet port in said cylinder covered by said secondary piston during said explosion, said secondary piston provided with means for preventing loss of pressure through said port. 105

4. A two-cycle internal combustion engine, comprising, in combination, a cylinder, primary and secondary pistons therein, a shaft, means connecting the primary piston with said shaft to rotate the latter, an inlet valve for admitting fuel into the cylinder above the secondary piston, exhaust and air admission ports in said cylinder adapted to be uncovered successively by said primary piston during the explosion stroke thereof, a valve in the secondary piston for allowing the fuel charge to pass 120 from above the same into the space between the pistons, and means actuated by said shaft for reciprocating said secondary piston and having provision for moving the same downward to scavenge out the burnt gases and hav- 125 130

ing provision for initiating upward movement of said piston to transfer the fuel charge through the piston valve into the space between the pistons after the primary piston 5 has covered the air admission port and exhaust port.

5. A two-cycle internal combustion engine, comprising, in combination, a cylinder, primary and secondary pistons therein, a shaft, 10 means connecting said primary piston with said shaft to rotate the same, means to admit fuel charges into the cylinder above the secondary piston, an exhaust port in said cylinder uncovered by the primary piston in 15 the course of the power stroke thereof, means to admit air into said cylinder after the primary piston has uncovered the exhaust port, valve means for allowing the fuel charge to pass from above the secondary piston into the 20 space between the pistons, and means actuated by said shaft for reciprocating the secondary piston and having provision for moving the same downward to scavenge out the burnt gases through the exhaust port.

25 6. A two-cycle internal combustion engine, comprising, in combination, a cylinder, primary and secondary pistons therein, means for reciprocating the secondary piston, and an intake valve for admitting fuel charges 30 into the space between the secondary piston and the cylinder head on inward movement of the secondary piston, said cylinder having a pair of exhaust ports located between the pistons when at their limit of approach and enabling introduction of a tool through one of 35 said ports visible through the other port for the purpose of removing carbon from the ends of said pistons.

7. A two-cycle internal combustion engine, 40 comprising, in combination, a cylinder, primary and secondary pistons therein, a shaft, a crank on said shaft, a rod connecting the crank to the primary piston, a cam driven by said shaft, and connections between the cam 45 and the secondary piston, said cam having a portion of varying radius for moving the secondary piston to and from the cylinder head and a portion of substantial length of uniform radius, the latter portion being 50 adapted to cause the secondary piston to dwell against the cylinder head, and said connections including yieldable means to prevent injury to the cam or connections while holding the secondary piston against the cylinder head.

55 8. A two-cycle internal combustion engine, comprising, in combination, a cylinder, primary and secondary pistons therein, a shaft, a crank on said shaft, a rod connecting said 60 crank to the primary piston, a cam driven by said shaft, and connections between said cam and the secondary piston, said cam having a portion of varying radius for moving the secondary piston to and from the cylinder head

and a portion of uniform radius for causing the secondary piston to dwell a substantial length of time in engagement with the cylinder head, said connections including spring means for preventing injury to the cam or connections while holding the secondary piston in engagement with the cylinder head. 65

9. A two-cycle internal combustion engine, comprising, in combination, a cylinder, primary and secondary pistons therein, a shaft, a crank on said shaft, a rod connecting said crank to the primary piston, a cam driven by said shaft, and connections between said cam and the secondary piston, said cam having a portion of varying radius for moving the secondary piston to and from the cylinder head and a portion of uniform radius and substantial length for causing the secondary piston to dwell in engagement with the cylinder head, said connections including spring 70 means for preventing injury to the cam or connections while holding the secondary piston in engagement with the cylinder head, and means to vary the tension of said spring means. 75

10. A two-cycle internal combustion engine, comprising, in combination, a cylinder, primary and secondary pistons therein, a shaft, a crank on said shaft, a rod connecting said crank to the primary piston, a cam driven by said shaft, and connections between the cam and the secondary piston, said cam having a portion of varying radius for moving the secondary piston to and from the cylinder head and a portion of substantial length for causing the secondary piston to dwell in engagement with the cylinder head, and said connections including yieldable means to prevent injury to the cam and connections as the secondary piston is moved into engagement with the cylinder head and away therefrom. 90

11. A two-cycle internal-combustion engine, comprising, in combination, a cylinder, primary and secondary pistons therein, a shaft, a crank on the shaft, a rod connecting the crank to the primary piston, and means actuated by said shaft for reciprocating the secondary piston including a stem for the secondary piston, a spring, and a member operating through the spring for imparting outward movements to said stem and secondary piston. 95

12. A two-cycle internal combustion engine, comprising, in combination, a cylinder, primary and secondary pistons therein, a shaft, a crank on the shaft, a rod connecting the crank to the primary piston, and means actuated by said shaft for reciprocating the secondary piston including a stem for the secondary piston, springs, and a member between and operating through the springs for 100 imparting inward and outward movements to said stem and secondary piston. 110

13. A two-cycle internal combustion en-

gine, comprising, in combination, a cylinder, primary and secondary pistons therein, a shaft, a crank on the shaft, a rod connecting the crank to the primary piston, and means actuated by said shaft for reciprocating the secondary piston including a stem for the secondary piston, springs on said stem, a member between and operating through said springs for imparting inward and outward movements to said stem and secondary piston, and adjustable means on the stem for varying the relation of the stem to said member.

14. A two-cycle internal combustion engine, comprising, in combination, a cylinder, primary and secondary pistons therein, a shaft, a crank on the shaft, a rod connecting the crank to the primary piston, and means actuated by said shaft for reciprocating the secondary piston including a stem for the secondary piston, a spring, a member operating through said spring for imparting inward movement to the stem and secondary piston, and adjustable means on the stem for varying the relation of the stem to said member.

15. A two-cycle internal combustion engine, comprising, in combination, a cylinder, primary and secondary pistons therein, a shaft, means connecting the primary piston with the shaft, an inlet port for admitting fuel charges to the cylinder, said port being covered by the secondary piston during compression and explosion of the fuel charges, and means for preventing loss of compression

through said inlet port during compression and explosion of the fuel charges. 35

16. A two-cycle internal combustion engine comprising, in combination, a cylinder, primary and secondary pistons therein, a shaft, means connecting the primary piston with the shaft, means actuated by the shaft for causing the secondary piston to reciprocate and seat against the cylinder head, and a fuel inlet port at a side of the cylinder for admitting the fuel into the space between the secondary piston and the cylinder head, 40 said port being located to be covered by a side of the secondary piston when the latter engages the cylinder head, thereby to prevent loss of compression through the inlet port during compression and explosion of the fuel 45 charges. 50

17. A two-cycle internal combustion engine comprising, in combination, a cylinder, primary and secondary pistons therein, a shaft, means connecting the primary piston to the shaft, means actuated by the shaft for causing the secondary piston to seat against the cylinder head, and a fuel inlet port at the side of the cylinder, said secondary piston being constructed and arranged to prevent loss of compression through the fuel inlet port during compression and explosion of the fuel charges. 55

In testimony whereof, I have signed my name to this specification.

CHARLES S. BARRELL.
